US00D346793S

United States Patent [19]
Iino et al.

[11] **Patent Number:** Des. 346,793
[45] **Date of Patent:** ** May 10, 1994

[54] ELECTRONIC COMPUTER

[75] Inventors: **Masaaki Iino, Yokohama; Osamu Kondo, Tokyo, both of Japan**

[73] Assignee: **Kabushiki Kaisha Toshiba, Kanagawa, Japan**

[**] Term: **14 Years**

[21] Appl. No.: **952,782**

[22] Filed: **Sep. 30, 1992**

[30] Foreign Application Priority Data

Apr. 3, 1992 [JP] Japan 4-9733
[52] U.S. Cl. **D14/100; D19/52**

[57] CLAIM

The ornamental design for an electronic computer, as shown and described.

DESCRIPTION

FIG. 1 is a top, front and right side perspective view of an electronic computer showing my new design;
FIG. 2 is a front elevational view thereof;
FIG. 3 is a rear elevational view thereof;
FIG. 4 is a left side elevational view thereof;
FIG. 5 is a top plan view thereof;
FIG. 6 is a bottom plan view thereof;
FIG. 7 is a top rear and left side perspective view thereof showing the lid of the memory card connector in an opened position;
FIG. 8 is a top plan view thereof showing the display in a word processor mode;
FIG. 9 is a top plan view thereof showing the display in a table calculation mode; and,
FIG. 10 is a top plan view thereof showing the display in a memorandum mode.
